(57) **CLAIM**

The ornamental design for a plate as shown and described.

DESCRIPTION

FIG. 1 is a perspective view of a plate showing the claimed design;

FIG. 2 is another perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof; and,

FIG. 9 is a partial enlarged view of FIG. 1 thereof.

The dot-dash broken lines encircling portion of the plate in FIG. 1 and illustrated in enlarged view in FIG. 9 form no part of the claimed design.
